[57] ABSTRACT

A technique for performing isotope ratio analysis is described which utilizes a negative ion mass spectrometer coupled with a negative ion duoplasmatron source. An untreated sample to be analyzed for a specific compound is diluted with a known amount of isotopic analog. The sample plus analog is volatilized if necessary, and purified by gas chromatography before entering the ion source. The extremely hot plasma of the duoplasmatron thoroughly fragments the large molecules and efficiently ionizes the input gas stream. The resulting ionized stream is analyzed in a magnetic mass spectrometer. The signals from a pair of peaks representing the common and noncommon tag isotope of the same element are converted to frequency signals and the frequency signals are converted to a ratio signal by a frequency ratio counter. The value of this ratio then indicates the precise amount of compound in the sample. The system operates very efficiently on stable, non-radioactive isotopes and is applicable to many analyses which cannot be performed with radioactive isotopes.

NEGATIVE ION DUOPLASMATRON MASS
SPECTROMETER FOR ISOTOPE RATIO
ANALYSIS

BACKGROUND OF THE INVENTION

1. Field of the Invention

The present invention relates to an isotope dilution analysis technique for detecting and quantitatively determining the quantity of compounds in fluids with a sensitivity approaching 10^{-12} grams per sample, and more particularly, to a technique for performing isotope ratio analysis by means of a negative ion mass spectrometer coupled with a negative ion duoplasmatron source.

2. Description of the Prior Art

The most effective and unambiguous way to follow the fate of a given material throughout any system is the use of "tags," which cannot be removed by any practical means. Isotopically-substituted molecules are such "tags." Organic molecules can be isotopically labeled by substitution of one or more of their atoms with a noncommon isotope, radioactive or stable. Such labeling makes the given molecules unique and allows their tracing through chemical, biological or even commercial systems.

One of the major problems in assessing the applicability of a drug for human consumption is to secure prior information on its biological half-life in circulation and its metabolic fate. It has been shown that it is very difficult and occasionally misleading to obtain this type of information from animal studies. The most appropriate way to obtain this information is to administer minute amounts of a labeled drug into the human system and to follow the change in its level in blood, urine, and feces. The need for a label is critical because conventional chemical analysis becomes impractical in most cases at concentrations below 10^{-9} moles (10^{-7} g). Up to date only radioactive isotopes provided a practical means for isotope dilution analysis.

The use of radioactive tracers in humans can be allowed in certain clinical situations but can hardly be justified for routine clinical analysis. Moreover, they are not generally admissible as tracers for commercial products which are likely to be consumed by humans. There is a calculated risk in the introduction of any amount of radioisotopes into a subject system, and one should avoid the exposure of any individual to a risk. The use of radioactive tracers in chemical diagnosis suffers from three drawbacks: (a) potential radiological damage which prevents its application for routine clinical analysis and limits it to adult patients; (b) the limited halflife of the isotopes approved for clinical use, which restricts their use to short-time tests and prevents extensive loading studies; and (c) where high sensitivity is required, high specific activities have to be used. Under these conditions there appear serious uncertainties about the chemical identity of the labeled material which might readily undergo chemical changes induced by its own radiation. It may be concluded, therefore, that the only way of tracing drugs by isotopic tagging through a sizable segment of the population is by using a nonradioactive isotope.

Many chemical elements found in nature consists of one isotope that constitutes over 90 percent of all the atoms, and one or more other isotopes that constitute a few percent or a fraction thereof (See Table I). The

isotopes D and ^{13}C are less abundant in nature than H and ^{12}C . Thus, natural methane (CH_4) will contain $1.108\% \text{ }^{13}\text{CH}_4$ and $4 \times 0.0148 = 0.0592\% \text{ }^{13}\text{CH}_3\text{D}$, but only $1.6 \times 10^{-4}\% \text{ }^{13}\text{CH}_3\text{D}$ and $9 \times 10^{-6}\% \text{ }^{12}\text{CH}_2\text{D}_2$.

TABLE I

Stable isotopes of atoms predominant in organic compounds

Element	"Common" mass	Isotope abundance, percent	"Uncommon" mass	Isotope abundance, percent
Hydrogen.....	H 1.007825	99.9852	D 2.014102	0.0148
Carbon.....	^{12}C 12.000000	98.992	^{13}C 13.003354	1.108
Nitrogen.....	^{14}N 14.003074	99.635	^{15}N 15.000107	0.365
Oxygen.....	16.0 15.994915	99.759	^{17}O 16.999133	0.037
Sulfur.....	32.8 31.972074	95.000	^{33}S 32.791462	0.204
			^{34}S 35.987090	0.760
			^{36}S 35.987090	0.014

The isotopic composition of nonradioactive compounds is assessed most accurately by mass spectrometry. A high resolution mass spectrometer ($M/\Delta M > 20,000$) can distinguish not only between, say $^{12}\text{CH}_4$ and $^{13}\text{CH}_4$, but also between $^{13}\text{CH}_4$ (mol wt = 17.034654) and $^{12}\text{CH}_3\text{D}$ (mol wt = 17.037577); $M/\Delta M = 17.038/0.0029 = 5,873$. Likewise, $^{13}\text{CH}_3\text{D}$ (mol wt = 18.040931) may be distinguished from $^{12}\text{CH}_2\text{D}_2$ (mol wt = 18.04385); $\Delta M = 0.0029$. This high resolution is necessary in practice because the mass spectrometric analysis using conventional electron bombardment ionization sources results in a complex fragmentation spectrum of the analyzed species. Taking a most elementary example: ethane, and using $\text{C}_2\text{H}_5\text{D}$ as tracer, one can obtain, with a certain electron impact ionization source, CH_3^+ as a predominant peak, but CH_2^+ , CH_4^+ , and CH_5^+ would also be present in the fragmentation spectrum to an extent depending on the geometry of the ionization source and gas pressure. Mass 16 may consist of $^{12}\text{CH}_2\text{D}^+$ (originating from the tracer molecule) plus $^{13}\text{CH}_3^+$ and $^{12}\text{CH}_4^+$. Mass 15 will include, in addition to $^{12}\text{CH}_3^+$, $^{13}\text{CH}_2^+$ and $^{12}\text{CHD}^+$. Mass 17 will consist of $^{12}\text{CH}_5^+$ plus $^{13}\text{CH}_4$, $^{12}\text{CH}_3\text{D}^+$, $^{13}\text{CH}_2\text{D}^+$, and $^{12}\text{CH}_2\text{D}_2^+$. Only a high resolution mass spectrometer analyzer can distinguish between these different species and allow the assessment of $^{13}\text{CH}_2\text{D}^+$ compared with $^{12}\text{CH}_3^+$, which gives a measure of the $^{12}\text{C}_2\text{H}_5\text{D}/^{13}\text{C}_3\text{H}_6$ ratio in the sample.

It is extremely difficult using high resolution mass spectrometry to make the ratios between the ionic fragments, such as CH_2^+ , CH_3^+ , CH_4^+ and CH_5^+ , reproducible enough to allow a quantitative determination of the isotopic composition of one of them, say CH_3^+ , with a high precision (better than 2 percent). Obviously, as one goes from the extremely simple cases of methane and ethane to realistic cases of drugs or metabolites which of, say, 10 carbon atoms and 20 hydrogen atoms plus oxygen, nitrogen and occasionally sulfur or phosphorus, the fragmentation pattern becomes increasingly complex, and a dozen different species may contribute to a certain mass number peak. Thus, the resolution of these samples into individual isotopic constituents may in many cases exceed the capabilities of even the best available high resolution mass spectrometer. It is for this reason that high resolution mass spectrometers, while useful in identification of unknown organic compounds through their fragmentation spectrum have a very limited capability in isotopic tracer analysis.

One possible way to overcome the difficulties in isotopic tracer analysis of organic compounds is to obtain

a representative sample of the isotopic species in an ionic form which contains only one to three atoms. This can be done by various chemical reactions such as oxidation to CO, CO₂, NO, N₂, H₂O etc., reduction to H₂ or exhaustive fluorination to yield O₂, N₂ and CF₄.

In the case of hydrogen isotopic determination, in organic compounds, for instance, the GC effluent is oxidized to H₂O over CuO and reduced to H₂ over Zn or U followed by further gas chromatograph separation before introduction into an MS. The two preliminary treatments require a minimum of 10⁻³g to avoid dilution by trace impurities and surface memory effects. The mass spectrum is complicated by the presence of H₃⁺ and requires several measurements at different pressures. As hydrogen constitutes only about 10 percent of most organic compositions the amount of sample required for precise measurement of H/O may be as high as 20 mg.

The present technique for determination of isotopic abundance of carbon involves oxidation of the test compound to CO₂ following gas chromatographic purification. An additional gas chromatographic purification stage is required, however, before introduction into the mass spectrometer because N₂O formed in trace amounts in the oxidation stage, as well as N₂O formed in the ion source from NO_x, would impair the precision measurement of masses 44 and 45. The relatively low sensitivity of the electron impact ionization source requires minimum amounts of 10⁻⁴ moles or 3 – 5 × 10⁻³g of CO₂ for precision determination.

Isotopic oxygen in organic compounds can be determined with a sufficient precision only by exhaustive fluorination, using highly elaborate instrumentation and techniques. Such a fluorination system can handle 10⁻³g quantities but 10⁻²g are most desirable in practice. Extraction of the oxygen from a sample purified by a gas chromatograph takes over 2 hours. This oxygen must now be repurified by gas chromatography to remove traces of F₂ and HCl (mass 36) prior to introduction into the mass spectrometer.

OBJECTS AND SUMMARY OF THE INVENTION

It is therefore an object of this invention to provide an improved technique for isotopic tracer analysis of compounds.

A further object of the invention is to provide an accurate technique for performing isotopic ratio analysis which greatly simplifies the measuring processes and improves the overall accuracy of the ratio measurement for a number of atomic species.

Yet another object of the invention is the provision of precision isotopic ratio analysis which can be performed with a much higher sensitivity and at a considerably lower cost than previously possible.

Still another object of the invention is the provision of an isotope dilution analysis technique for detecting and quantitatively determining drug levels in body fluids with the sensitivity approaching 10⁻¹² gram per sample.

These and other objects and many attendant advantages will become apparent as the description proceeds.

The analysis technique in accordance with the invention performs isotopic ratio analysis by negative ion mass spectrometric analysis on a negative ion stream generated in a duoplasmatron source. This combination of devices greatly simplifies measurement and im-

proves the overall accuracy of the ratio measurement for a number of species. To a sample containing an unknown concentration of a known compound, a known amount of the same compound with a different isotopic composition is added. The combined mixture is preliminarily volatilized, if necessary, and impurities may be removed by subjecting the sample to gas chromatography before it is fed into the negative ion duoplasmatron source.

10 A carrier gas separator such as a ceramic disc or a organic plastic membrane permits the rejection of a major portion of the carrier gas and introduction of most of the compound and analog (> 80 percent) into the ion source. The duoplasmatron has the unique 15 combined characteristic that it utilizes an extremely hot plasma which thoroughly fragments large molecules and that it efficiently ionizes the input gas molecules yielding a net ionization efficiency of between 1 and 10 percent. The mass peak ratios of selected isotopic ions are monitored at the output of a multiple mass peak magnetic mass spectrometer. It is then possible to 20 measure the ratio of the sample compound to the isotopic compound with an accuracy of 1 percent.

The sensitivity of the negative ion duoplasmatron 25 mass spectrometer which is higher by over six orders of magnitude than that of conventional isotope mass spectrometers allows the determination of unknowns down to 10⁻¹² gram amounts. The negative ion mass spectrum is considerably more simple than the positive ion 30 counterpart. This is because not all atoms and molecules have an electron affinity and double negative ionization does not exist as does double, or even higher, positive ionization.

35 As a consequence relatively unambiguous, isotope ratios for certain atomic species can be measured in the presence of numerous other species using negative ion mass spectrometry. For example, the ratio of H⁻/D⁻ can be measured unambiguously since no other negative ions with mass numbers of 1 or 2 exist. H₂⁻ is 40 unstable and has never been observed. The measurement of the ratios H₂⁺/HD⁺ and H₂⁺/D₂⁺ using positive ions is complicated by the presence of H₃⁺ and ⁴He⁺⁺. To measure the isotopic ratio ¹²C/¹³C 45 one must observe the ratio of ¹²CH⁻/⁽¹³CH⁺ + ¹²CD⁻) and subtract out the contribution of ¹²CD⁻ by knowing the H/D abundance ratio. One could also use the CN⁻ molecule to measure the ¹²C/¹³C ratio if the ¹⁴N/¹⁵N ratio is known. Or conversely if the ¹²C/¹³C ratio 50 were known; the ¹⁴N/¹⁵N ratio could be measured by observing ¹²C¹⁴N⁻/⁽¹²C¹⁵N⁺ + ¹³C¹⁴N⁻). Oxygen and sulfur isotopes could also be determined as OH⁻ (masses 17, 18, and 19), O₂⁻ (masses 32, 33 and 34) SO⁻ (masses 48 to 52) and S₂⁻ (masses 64 to 72^{1/4}.

55 The method of the invention can be used to determine drug concentrations in body fluids. For instance, the body fluid sample may be combined with a known amount of an isotopic analog of the drug which has its minor isotopic component of ¹³C or D altered from the naturally occurring isotopic concentration. The same technique may also enable the tracing of label drugs administered to humans when present in ppb concentrations. The technique should also make practical the labeling of commercial drugs for the identification of the manufacturer or for the date of production. Time required for complete analysis should be between 30 and 60 minutes and at moderate cost per assay.

The novel, highly sensitive mass spectrometric technique of the invention can be applied to numerous pharmacological, toxicological and physiological problems. The method can be utilized to determine the persistence and fate of drugs in humans at subpharmacological levels, to determine and assess unknown pharmacological or toxic agents in clinical samples and to determine the biological half-life and fate of physiological constituents and nutrients.

These capabilities will facilitate the testing of new drugs and will aid in clinical treatment of subjects suffering from poisoning and in forensic medicine. The method will also advance fundamental clinical studies of human nutrition and physiology and will promote better control of drug distribution and prevention of drug abuse.

Organic molecules labeled with stable isotopes, primarily deuterium (D) and ^{13}C can be used in the performance of the desired analysis. Only the determination of source or date of production of drugs require the administration of labeled compounds to humans. The other analyses can be performed by applying isotopic dilution analysis at the analytical stage in the laboratory.

The method of the invention can also be utilized with radioisotopic species and in nonpharmacological applications. For example, carbon dating can be performed to count very low count rates of ^{14}C by determining the ratio of $^{26}\text{CN}^-/^{28}\text{CH}^-$. CN^- which occurs at mass numbers 26, 27 and 28 will reflect the isotope populations of ^{12}C , ^{13}C , ^{14}N , and ^{15}N . CN^- is an extremely stable negative ion, (electron infinity of about 3.6 eV) and will present a dominant negative ion peak in discharges containing nitrogen and carbon. Thus, this technique will be quite superior to the classical counting techniques now utilized in carbon dating.

The invention will now become better understood by reference to the following detailed description when considered in conjunction with the accompanying drawing.

BRIEF DESCRIPTION OF THE DRAWING

The FIGURE is a schematic view of a duoplasmatron mass spectrometer apparatus for producing the invention.

DESCRIPTION OF THE PREFERRED EMBODIMENTS

Referring now to the FIGURE, a mixture of the sample and a precise amount of an isotopic analog thereof are fed into the inlet 12 to the vaporizer 10, such as a retort. The vaporized mixture is dispersed in carrier gas introduced with the sample at 12. The dispersion is separated into bands within the gas chromatograph 16. The impurity bands are vented if they are eluted first. The band containing the mixture of isotopic compounds is then separated from most of the carrier gas by a silicone rubber membrane 14 and introduced into the inlet 18 of the duoplasmatron negative ion source 20.

In the duoplasmatron an intense, high pressure arc is produced by the combination of electric and magnetic fields. The intensity of this arc permits efficient extraction of negative ions from a very small aperture which is typically 0.10 inch in diameter. Many such sources have been developed for use in tandem accelerators and in negative ion collision studies. A very suitable

source of negative ions for beam energies of less than 5,000 eV is disclosed in "The Review of Scientific Instruments," Vol. 38, No. 6, 745-748, June 1967.

In this source, the arc axis is offset from the ion beam axis by offsetting the anode extraction aperture a small distance, typically 0.020 inch, from the center of the arc. This prevents loading of the negative ion beam with electrons from the arc. Since the strong magnetic field tends to confine the electrons to the center of the arc more efficiently than the heavier negative ions, the offset aperture effectively blocks the extraction of electrons.

Referring again to the FIGURE, the source 20 comprises an arc section 22 and a focussing section 24. The source is housed in a container 26 maintained at a low pressure by a vacuum pump 28, typically about 2 to 10×10^{-2} Torr. The arc is struck between a cathode 30 and an anode 32. The Z-electrode 34 helps to confine the arc to a narrow axial pencil. The Z-electrode is slightly displaced from the beam axis. A magnetic coil 36 coaxially surrounds the cathode 30 and Z-electrode 34. The anode 32 is suitably a disc having a central output aperture 34. The disc which is coaxial with the electrostatic focussing electrodes may be displaced from the Z-electrode axis.

As the separation band dispersed in carrier gas enters the arc, the compounds are efficiently fragmented into ionized components by the hot plasma. The negative ion stream leaves the arc section 22 through the offset aperture 34. The beam is focussed by means of electrostatic focussing electrode 40, 42, 44 and by means of deflector shims 46, 48.

The focussed beams then pass through the entrance slit 50 of the mass spectrometer 52. The negative ions in the beam are dispersed by the magnetic field of the mass separator and enter the slits 54 provided in the target collector 56.

The detection system of the mass spectrometer consists of a separate electron multiplier detector 60, 62, 64, 66 coupled to ground by a high impedance resistor 68. The detectors are positioned behind each slit 54. A voltage to frequency converter 70 converts the output voltage of each multiplier to a proportional frequency signal. The signals from a pair of detectors (60-62 and 64-66) are applied to a frequency ratio counter 72 which provides a ratio output signal which is recorded on recorder 74.

The ratio signal output is calibrated by observing the ratio produced from a natural sample and a pure isotopic tracer sample. Standard state of the art electronics enables measurement of signal ratios with a precision of one part in 10^5 .

The carrier gas can be inert or reactive with the compound and analog. If an organic compound containing hydrogen and carbon along with N_2 as a carrier gas are introduced into a negative ion duoplasmatron source, extensive fragmenting of the drug molecule will occur and a negative ion mass analysis will yield a highly selective distribution of a few negative ions. Thus, unlike the positive ion counterpart, masses 1 and 2 will truly reflect the isotope population of H and D, since H_2^- does not exist. Similarly CN^- which occurs at mass numbers 26, 27, and 28 will reflect the isotope populations of ^{12}C , ^{13}C , ^{14}N , and ^{15}N . CN^- is an extremely stable negative ion (electron affinity of about 3.6 eV) and represents the dominant negative ion peak in discharges containing nitrogen and

carbon. Thus, when standard nitrogen gas is used as the carrier gas, the ratios of the mass peaks occurring at mass numbers 1 and 2, and 26 and 27, will be a sensitive indication of the relative isotopic abundance of hydrogen and carbon. Nitrogen by itself does not produce a stable negative ion and therefore will not appear as N_2^- in the extracted ion beam.

If an inert carrier gas is used, say argon, with nitrogen-containing carbon compounds, the CN^- peaks will reflect the relative abundance of both ^{13}C and ^{15}N . Oxygen isotopic analysis may be performed on OH^- ions (masses 17 to 19) which will be predominant in the presence of excess hydrogen, or on O_2^- (masses 32 to 36) which may, however, be contaminated with traces of HO_2^- ions. (The latter may interfere with the determination of ^{17}O but not of ^{18}O abundance.) The isotopic compositions of some of the sulfur isotopes can be determined using the SO^- peak (mass 48 to 54) formed in the presence of excess oxygen as the carrier gas. Owing to the possible formation of the SOH^- ion, only ^{32}S , ^{34}S , and ^{36}S might be analyzed in this manner.

Considering the present cost of enriched stable isotopes, only D and ^{13}C are available at reasonable prices, and thus most analyses will be performed with these two elements. It is conceivable, however, that as soon as a demand develops for ^{15}N , ^{18}O , or ^{34}S , these isotopes could be separated at a cost comparable with that of ^{13}C .

The technique may be practiced either by tagging the unknown compound or metabolite with the uncommon isotope or by tagging the added analog with the uncommon isotope.

There remains the question of the safety of administration of small quantities (10^{-10} moles) of nonradioactive labeled pharmaceuticals to human subjects. The difference in physiological or pharmacological action of the labeled compound and its natural analog (which contains the same isotopes at a lower concentration) is expected to be minimal. In no case should the D-substituted compounds carry the label on easily dissociated hydrogens (where a considerable difference in physiological or pharmacological activity is expected). These hydrogens readily undergo isotopic exchange with water or other labile hydrogens and thus they are unsuitable as biological tracers.

Isotopic labeling of the administered pharmaceutical followed by separation and isotope ratio analysis with the addition of the normal, common isotopic form allows quantitative determinations of drug levels down to 10^{-12} g quantities. Even at assay levels of 10^{-11} g, the technique is four orders of magnitude better than conventional chemical analysis. Such a sensitivity allows the administration of quantities as low as 10^{-8} g of a drug to a human subject and still follows its fate with a fair degree of confidence. The method of the invention enables isotope dilution analysis to be accurately performed with stable, non-radioactive isotope.

The sensitivity attainable by the method of this invention is in fact higher than that obtainable by using radioactive tracers. For comparison, using tritium or ^{14}C as tracers, one can determine with a similar precision within the same time period only 3×10^{-14} moles of T and 2×10^{-11} moles of ^{14}C . Taking singly labeled molecules of mol wt 200, these quantities correspond to 6×10^{-12} g and 4×10^{-9} g, respectively. In other words, the present method using stable isotopic tracers for hy-

drogen has as high a sensitivity as that obtainable by the radiotracer methodology and by far a higher sensitivity than by using radiocarbon as tracers. If one remembers that it is practically impossible to label a compound with a carrier-free tracer, whereas stable isotopes can be readily handled up to 100 percent purity, it may be concluded that the method of the invention is in fact more sensitive. Furthermore, the present method allows the use of ^{18}O and ^{15}N as tracers with a comparable sensitivity. There is no practical radiotracer for these elements.

Another method of acquiring information on the fate of new drugs at subpharmacological doses is by the administration of the tested compound as such (with its natural isotopic composition) and using a stable, labeled or multilabeled compound as the known amount of isotopic analog. For example, one may administer 100 mg of $C_9H_8O_4$ (aspirin) into a human subject and recover 0.01 mg in a blood sample. Now one may add to it one mg of $C_9H_5D_3O_4$, 98 percent D of the formula:

This mixture is then separated by a gas chromatograph and introduced into the duoplasmatron mass spectrometer. The D/H ratio in the carrier ($3 \times 0.98 + 1.45 \times 10^{-4} \times 5)/8 = 0.36841$ is changed to $(3 \times 0.98 + 5 \times 1.45 \times 10^{-4} + 8 \times 1.45 \times 10^{-4} \times 10^{-2}) = 0.36476$. The difference $\Delta = -0.00364$ can readily be determined with a precision of ± 1 percent, which will also be the precision of determination of the amount of the drug present in the blood.

In view of the relatively high natural abundance of ^{13}C , one could use ^{13}C -depleted carbon as a tracer in biological systems using compounds labeled with enriched ^{13}C as the known analog for isotopic ratio analysis. Alternatively, the isotope-depleted compounds may be used as the known analog. For example, one may use barbital $C_8H_{12}N_2O_3$ with its ethyl carbons depleted to 10 percent of its natural abundance as a tracer. This compound will contain $(4 \times 1.108 \times 10^{-2} + 4 \times 1.108 \times 10^{-3}) / (8 \times 98.892) = 0.6170$ percent ^{13}C compared with 1.124 percent of its natural isomer. Taking such labeled barbital as tracer and using a 1:50 dilution factor, the addition of natural barbital as known analog would result in a change from 1.124% ^{13}C to 1.114 percent, which can be determined with ± 1 percent precision with the duoplasmatron system. Taking natural barbital as tracer and the depleted barbital as the known analog, the ^{13}C abundance would change from 0.617 percent to 0.627 percent, which can again be determined with ± 1 percent precision. As the amounts necessary for analysis in the highly sensitive system of the invention are as low as 10^{-9} g, the amount of drugs to be determined with ± 1 percent precision is as low as 10^{-11} g. If lower precision is required or if special care is taken in the gas chromatography, quantities down to 10^{-12} g of drugs can be determined with ± 10 percent precision.

No health hazard whatsoever is involved in the tagging of organic compounds intended for general human consumption by double or triple-labeled molecules at concentrations of 1:10⁶. Let us take, for example, the case of a compound tagged by the addition of a 10⁻⁶ mole fraction of molecules triple-labeled with deuterium. Let us assume that the given compound contains 12 hydrogen atoms (e.g., barbital). The total amount of

hydrogen in 1 g of barbital is $12/184.2 \times 1,000 = 65$ mg containing 10ng D. Now 1mg of the triple-labeled barbital, which is sufficient to make 1g barbital identifiable, contains $6,000/186.2 = 36$ mg D. In other words, by tagging the barbital, its D content has been increased by about one part in 300. The latter is considerably smaller than the inaccuracy inherent in the dosage of pharmaceutical products. In fact, no commercial drug is free of impurities at the parts-per-million level and these impurities must have by far more pronounced side effects than any isotopically-substituted molecule of the drug itself.

The possible adverse biological effects of ^{13}C , ^{15}N , or ^{18}O are smaller by two orders of magnitude than those of D, as can be concluded from their measured kinetic isotope effects. The former isotopes may thus be used as tracers even at carrier-free levels, and there should evidently be no doubt regarding their safety at 10^{-6} levels of dilution.

Another application of the isotope dilution methodology is in the identification of unknown drug or poison in a clinical sample (for purposes of treatment of a poisoned subject or in forensic cases). To aliquots of the biological sample, small amounts of different suspected drugs, narcotics, or organic poisons enriched with a certain stable isotope are added. Each of these spiked samples is then chemically treated to separate a small quantity of the added constituent. This will now be subject to isotopic analysis and its isotopic composition compared with that of the original labeled drug. Only the sample which contained the particular drug will affect the isotopic composition of the added stable isotopic compound, while those cases in which no change in isotopic composition took place on addition to the clinical sample may be excluded from the list of suspected poisons. A quantitative assessment of the concentration of the suspected poison can be obtained simultaneously in this screening test according to this invention.

The principles outlined above for testing new drugs on human subjects can be applied to testing of the persistence and fate of physiological constituents, e.g., hormones, nutrients, and coenzymes. In each case, one can use either isotope-enriched or isotope-depleted compounds, either as tracers or as carriers. It is evident that the number of applications of this methodology for clinical diagnosis and for a better understanding of physiological processes is practically unlimited.

The existence of a rapid and precise method of the invention for the determination of isotopic ratios in organic molecules will find application in the control of the distribution of pharmaceuticals. If all the production of a certain manufacturer is uniquely tagged, this product may be identified and distinguished from any other drug of the same composition. Different manufacturers may thus be individually identified by using different unique labeling of the same molecules.

Identification of a certain batch of drugs may be important if the expiration of drug effectiveness is critical. Each batch can be uniquely tagged by using different combinations of isotopic substitution on the molecule, such as 3D, 3D + ^{13}C , 3D + ^{15}N , ^{13}C + ^{15}N + D, and others. D, ^{13}C , and ^{15}N at five different relative concentrations in the molecule may give over 100 different distinguishable combinations. This may allow changing the labeling every month for eight years of production without repetition of the code.

As examples of various other specific clinical and pharmaceutical uses of the method, the amount of glycine in human urine can be determined by isotopic ratio analysis of urine samples diluted with D_2 glycine as the uncommon isotopic analog. Similarly, the concentration of acetone in urine of normal and slightly diabetic subjects can be determined using D_6 acetone as the uncommon isotopic analog. The metabolism of ethanol can be determined by injecting $\text{C}_2\text{H}_5\text{OH}$ or $\text{C}_2\text{D}_5\text{OH}$ into rats followed by isotopic dilution analysis of blood samples with the isotopic analog at dilution ratios of 1:10⁴ to 1:10⁵. The metabolism of ^{13}C -labeled carboxyl-phenylacetic acid by rats may be determined by monitoring the exhaled carbon dioxide for ^{13}C .

The degree of dilution of the sample with isotopic analog will vary from case to case and will depend on the size of the sample, the natural abundance of the non-common isotope and the sensitivity of the detection system for the negative ions of interest. Isotopic dilution analysis in most cases can be practiced with dilution ratios from about 1:25 to about 1:10⁷.

The sensitivity and precision of the system may be demonstrated by the following example. Let us assume that a 10^{-10} g sample of molecules of molecular weight 200 is used and that each 100 molecules produces one CN^- ion. This estimate is conservative since each molecule is likely to contain many carbon atoms. The total number of ions produced by the sample is $(10^{-10}/200) \times 6 \times 10^{23} \times 10^{-2} = 3 \times 10^9$. Of this number, about 1 percent or 3×10^7 will be due to $^{13}\text{CN}^-$ and about 0.4 percent will be due to $^{12}\text{C}^{15}\text{N}^-$. The noise attributed to the $^{13}\text{CN}^-$ signal due to isotope fractionation will be 3×10^5 particles and represents its dominant source of uncertainty.

Another source of uncertainty can arise from organic impurities. These must be separated from the components of interest by gas chromatography. The minimum sample size is therefore limited by the resolution of the gas chromatograph consequently, a sample of 10^{-8} g would be an average sample in the system of the invention, though samples of 10^{-10} g to 10^{-1} g can be processed depending on resolution and capacity of the source and mass spectrometer. Following the same calculation, a sample of 10^{-8} g could be determined with an ultimate precision of $\pm 2 \times 10^{-5}$.

The effectiveness of isotopic dilution analysis can be demonstrated by the following analysis. The instrument is utilized to measure the ratios of masses $\text{H}^-/\text{D}^- = R_H$ in a mixture of an isotopically labeled isotope added to a urine sample. The diluted mixture is introduced into the gas chromatograph-mass spectrometer combination. Since the natural abundance of D is only 1.48×10^{-4} of H,

$$R_H = (x+ay)/y(100-a)$$

where x represents the amount of drug to be measured in the sample, y the amount of isotopically substituted drug added, and a is the percentage of H in the labeled compound. It is assumed, for simplicity, that the amount of natural D in the sample is negligible compared to the added D isotope. Solving for x, one obtains

$$x = y[100R_H - a(R_H + 1)]$$

In the case of masses $\overline{26}$ and $\overline{27}$, the analysis is somewhat more complicated owing to the presence of ^{15}N

(0.365 percent) and the higher concentration of ^{13}C (1.108 percent). Assuming no change in the isotopic composition of nitrogen:

$$R_{CN} = \frac{26}{27} = (\text{ $^{12}\text{C}^{14}\text{N}$ })/(\text{ $^{13}\text{C}^{14}\text{N}$ } + \text{ $^{12}\text{C}^{15}\text{N}$ })$$

$$R_{CN}^{-1} = \frac{27}{26} = \frac{(\text{ $^{13}\text{C}^{14}\text{N}$ } + \text{ $^{12}\text{C}^{15}\text{N}$ })/\text{ $^{12}\text{C}^{14}\text{N}$ }}{\text{ $^{13}\text{C}^{14}\text{N}$ }/\text{ $^{12}\text{C}^{14}\text{N}$ } + \text{ $^{12}\text{C}^{15}\text{N}$ }/\text{ $^{12}\text{C}^{14}\text{N}$ }} = R_C^{-1} + 3.66 \times 10^{-3}$$

$$R_C = R_{CN}/(1 - 3.66 \times 10^{-3} R_{CN})$$

$$R_C = (98.892 x + ay)/[1.108 x + (100 - a)y]$$

$$x = \left\{ [100 R_C - a(R_C + 1)]/(98.892 - 1.108 R_C) \right\} y$$

The accuracy of the measurement of R will depend on the accuracy in determining the values of a and y as well as the uncertainty in the ^{13}C isotopic abundance in x . Since a and R can be determined to a higher precision than the dilution factor x/y , which is approximately ± 1 percent, this will be the precision with which x can be determined. This estimate neglects possible background errors due to limited resolution of the gas chromatograph. The limitation in sensitivity of this technique will probably be due to the resolution of the gas chromatograph. A sensitivity of 10^{-12}g with an accuracy of 10 percent is attainable with a capillary gas chromatograph.

The analysis system of the invention provides an indicative, representative sample of the isotopic species in a form containing only one to three atoms without the necessity of chemical pretreatment. Due to increased sensitivity, the amount of sample necessary for analysis will be reduced by several orders of magnitude. The technique is fast and efficient and the apparatus is more simplified.

It is to be understood that only preferred embodiments of the invention have been described and that numerous substitutions, alterations and modifications are all permissible without departing from the spirit and scope of the invention as defined in the following claims.

What is claimed is:

1. A method of determining the quantity of a substance in a sample comprising the steps of:

adding a measured amount of an isotopic analog of the substance to the sample to form a mixture; ionizing and fragmenting the mixture in a hot plasma to form ionized fragments of the substance and isotopic analog;

extracting the negative ion fragments as a beam from the hot plasma;

magnetically separating the beam into a first and second beam corresponding to negatively ionized fragments of the substance and negatively ionized fragments of the isotopic analog;

measuring the intensity of said first and second beams; and

rationing the measured intensities of said first and second beams, whereby the quantity of said substance in said sample may be determined.

2. A method according to claim 1 further including the step of vaporizing said mixture.

3. A method according to claim 1 further including the step of purifying said sample.

4. A method according to claim 3 in which the mixture is purified by passage through a gas chromatographic column.

5. A method according to claim 1 further including the step of dispersing said mixture in a carrier gas.

6. A method according to claim 5 in which the carrier gas is unreactive with the sample.

7. A method according to claim 5 in which the carrier gas reacts with the sample to form ionized fragments containing said isotope.

8. A method according to claim 7 in which the carrier gas is selected from a group consisting of nitrogen, oxygen and hydrogen.

9. A method according to claim 1 in which the isotope is non-radioactive.

10. A method according to claim 1 in which the sample contains a first isotopic concentration and the analog contains a substantially different isotopic concentration.

11. A method according to claim 1 in which the isotopes are selected from a group consisting of D, ^{13}C , ^{15}N , ^{18}O , and ^{36}S .

12. A method according to claim 11 in which the substance contains a first concentration of at least one of said isotopes and the analog contains a lower concentration of said isotopes.

13. A method according to claim 11 in which the added analog contains a higher concentration of said isotopes.

14. A method according to claim 1 in which the substance and analog are organic compounds containing at least one of the atoms selected from the group consisting of C, H, O, N and S and isotopes thereof.

15. A method according to claim 14 in which the sample is a biological fluid and said isotopes are substituted on non-labile positions of said compound that are not dissociated by the biological system of the animal subject.

16. A method according to claim 1 in which the dilution ratio of said substance to said analog is from 1:25 to 1:10⁷.

17. A method according to claim 16 in which the sample contains from 10^{-1} grams to 10^{-10} grams of said substance.

18. A method according to claim 15 in which said sample is a pharmaceutical and further including determining the persistence level of the pharmaceutical by administering a material selected from the group consisting of said pharmaceutical and an isotopic analog thereof to a subject, recovering a sample of body fluid of the subject containing said material, adding a known amount of said isotopic analog to said sample to form said mixture.

19. A method according to claim 1 in which said mixture is ionized and fragmented in a negative ion duoplasmatron.

20. A method of determining the identity of an unknown first substance comprising the steps of:

adding known amounts of isotopic forms of known different second substances to different aliquots of said first substance to form different mixtures, one of said different second substances being suspected as being the same as said unknown first substance; successively, for each different mixture, ionizing and fragmenting the mixture in a hot plasma to form a beam of negatively ionized fragments;

magnetically separating the beam into a first beam path corresponding to the negatively ionized fragment of the said isotope and a second beam corre-

sponding to the negatively ionized fragments of the first substance;
measuring the intensity of the first and second beams, and
observing the presence of a characteristic ratio of 5 said first and second beams as an indication of the identity of said first substance.

21. A method of identifying a batch of an organic chemical comprising the steps of:
labeling the batch by adding a known amount of non- 10 common isotopes to the batch at non-labile, non-dissociative positions of the chemical;
recording the labeling information;
forming a mixture of a known amount of a sample of the labeled compound and a known amount of a 15

common isotopic analog thereof;
introducing the mixture into a hot plasma to form a beam of negatively ionized fragments;
magnetically separating the beam into a first beam path of the negatively ionized fragments containing the non-common isotope and a second beam of the negatively ionized fragments containing the common isotope;
measuring the intensities of the first and second beams;
determining the isotopic content of the chemical; and comparing it to the recorded labeling information.
